UNITED STATES PATENT OFFICE.

MICHAEL PARIDON, OF BARBERTON, OHIO. ASSIGNOR TO THE DIAMOND MATCH COMPANY, OF CHICAGO, ILLINOIS, A CORPORATION OF ILLINOIS.

MACHINE FOR MAKING MATCH-BOOKS.

1,272,510.

Specification of Letters Patent. Patented July 16, 1918.

Application filed September 28, 1917. Serial No. 193,640.

To all whom it may concern:

Be it known that I, MICHAEL PARIDON, a citizen of the United States, and resident of Barberton, in the county of Summit and 5 State of Ohio, have invented certain new and useful Improvements in Machines for Making Match-Books, of which the following is a specification.

In Letters Patent of the United States 10 No. 1,042,472, dated October 29, 1912, is disclosed a machine for the production of match books comprising match cards having foldable covers fastened thereto. The said machine includes, in its construction, 15 mechanism whereby flexible cover blanks are successively fed from a suitable magazine, folded at one end, and introduced at intervals to the links of an intermittently-movable endless carrier by means of which they 20 are advanced to a station where match cards are accurately positioned and pushed into the opposing folded ends of covers in the carrier. This carrier transports the cards and covers thus assembled to mechanism 25 whereby they are fastened together; thence to devices whereby frictional ignition substance is applied to the covers; thence through an extended drying path and back 30 near to the cover magazine. Thereupon the match cards with their attached covers are transferred from the carrier to devices whereby outwardly-extended portions of the covers are bent over the outer sides of the match cards and the free ends of the flaps 35 thus formed are snugly tucked in under the edges of the fastened folds.

The object of the present invention is to insure the passage of the free end of the flap of each cover beneath the edge of the fastened fold thereof; and, accordingly the invention, broadly stated, comprises in a 40 book-match machine, means whereby the extended portion of the cover is transversely bent preparatory to its presentation to the tucking devices.

More specifically, the invention comprises means for the purpose mentioned embodying a rotary presser device which is so constructed and arranged in relation to the 45 path of the cover flaps, as to act upon and impart a transverse bend to the said flaps in succession before their delivery to the turning over and tucking devices of the book-match machine.

The invention also comprises features of 55 construction and combinations of parts which will be hereinafter described and claimed.

In the drawings—

Figure 1 is an elevation, partly in section, 60 of a portion of the endless carrier and supporting parts of a match-book machine embodying my invention.

Fig. 2 is a transverse vertical section, as on the line 2—2 of Fig. 1, illustrating the 65 operation of the presser wheel and adjuncts on the flap extension of a match book cover.

Fig. 3 is a sectional elevation, enlarged, of 70 the presser-wheel and associated parts, also illustrating the flap bending operation.

Fig. 4 is a perspective view of one of the 75 links of the carrier, showing therein a match book with its flap extension.

Fig. 5 is a sectional elevation of the flap folding and tucking mechanism for the 80 match book.

Figs. 6, 7 and 8 are perspective views 85 illustrating successive steps in the flap tucking operation.

Referring to the drawings, 10 designates 90 a portion of a preferred form of endless carrier for a succession of match-books, which carrier comprises hingedly connected link members in which the match cards *a* and covers *b* are assembled and bound together 95 in book-like form, with one end of each cover extending beyond the adjacent edge of the carrier so as to provide a flap *c* which may be folded over upon the matches, and the outer end of the flap then be securely tucked 100 beneath the free edge of the fastened narrow fold *d* at the opposite end of the cover. The carrier is supported and guided by suitably-arranged wheels 11 mounted on shafts 12 carried by the supporting frame work 13 105 of the machine.

The flap folding and tucking mechanism herein selected to illustrate the invention is similar in construction and operation to that set out in Patent No. 1,042,472 above referred to. As shown in Fig. 5 this mechanism comprises an intermittently-rotatable turret wheel 14 having radial pockets 15 which receive the bodies of the match books, pair by pair, as rapidly as they are ejected 110 from the carrier by the rearward movement of one head 16 of a double-headed plunger. The cover flaps *c* extend outwardly beyond

the wheel 14 and as the books progress therewith such flaps impinge against a suitably-arranged folding member 17 having a rearward horizontal extension 18 which overlies a channel 19 in the main frame. This channel is in alinement with a pair of pockets of the wheel, when the wheel is at rest, so that when a pair of books is being inserted into the wheel from the carrier another pair is being ejected from the wheel and into the channel by the rearward stroke of the other head 20 of the plunger. The cover flaps of the succeeding pairs of books are thus folded upon the matches of the respective books by the successive actions of the folding member and its rearward extension upon the flaps. The books, with their folded cover flaps, are discharged directly upon a rearward yielding shelf 21 and beneath two reciprocating pads, whereof one is shown at 22. These pads are supported by curved members formed on one end of an arm 23 which is jointed at its opposite end to an oscillating lever 24 and thereby moved to and fro longitudinally of the adjacent cover flaps. The arm 23 overhangs the pocketed wheel and is provided with a cam projection 25 which is maintained in the path of a series of suitably-spaced peripheral studs or tappets 26 on the wheel; such studs or tappets as they successively pass beneath and escape the cam projection raising and permitting the descent of the arm in such a manner as to move the pads upon and from the underlying cover flaps of the successive pairs of match books. By the compound motion thus imparted to the pads they are periodically brought into frictional contact with the cover flaps as seen in Fig. 6, the flaps moved slightly rearward as seen in Fig. 7 and then forward as seen in Fig. 8, so as to push the free ends of the flaps beneath the edges of the fastened folds of the respective covers as fully described in Patent No. 1,042,472 aforesaid.

In order to insure the passage of the ends of the cover flaps beneath the fastened folds I provide the machine, in advance of the folding and tucking mechanism, with devices whereby the flaps are transversely bent in such a manner that the free ends of the flaps, when they are folded over, tend to bear upon the tops of the match cards, and thus obviate the otherwise liability of such ends sliding over upon or impinging against the opposing edges of the fastened folds during the inserting action of the tucking pads. The flap bending devices, in the preferred form illustrated, are constructed and arranged to act upon the flap extensions *c* of the covers as they are carried about one of the chain guide wheels 11 of the machine. These wheels are each provided with a circumferential edge flange 27 for the guidance of the carrier, which

flange is so disposed that the successive flap extensions of the cover overhang the flange as they progress with the carrier. Fastened to the said wheel 11, co-axially therewith and in spaced facial relation thereto, is a similar wheel 28 having a circumferential edge flange 29 positioned to serve as a rest for the outer portions of the successive flap extensions as they pass about the proximate guide wheel. A freely rotatable presser wheel 30 is so disposed that its periphery, which is preferably rounded in cross section, extends slightly into the upper portion of the space between the flanges of the pair of wheels 11, 28. This presser wheel 30 is loosely mounted on a stud-shaft 31 extending from a bracket 32 on one of the frame posts of the machine.

By the construction just described it will be seen that as the successive cover flaps *c* pass beneath the presser wheel, such flaps are transversely supported at two separated points by the spaced flanges 27, 29 of the wheels 11, 28, respectively; and the presser wheel acts with a rotary ironing effect to 90 depress the bodies of the flaps into the adjacent space between the flanges, *i. e.*, between the fold line and the outer end of each flap, thereby imparting a downward bend or bow to the flaps in succession, as 95 indicated in Figs. 2 and 3. Hence when each flap is subsequently folded over upon the matches the flap is humped or arched and its free end is downwardly inclined to insure its passage beneath the edge of the 100 retaining fold *d* of the match book, as above described.

It is to be understood that my invention is not limited to the specific construction and arrangement herein disclosed as the same 105 may be variously modified within the principle of the invention and the scope of the appended claims.

I claim—

1. In a machine for making match books comprising associated matches and flexible covers, each of said covers including a retaining fold at one end and an outwardly extending flap at the opposite end thereof, the combination with means for advancing 110 said books in succession, of a presser device positioned to act upon the cover flaps of the successive books in a plane between the fold line and the outer end of each flap, thereby imparting a transverse bend to the 120 body of the flap.

2. In a machine for making match books comprising associated matches and flexible covers, each of said covers including a retaining fold at one end and an outwardly 125 extending flap at the opposite end thereof, the combination with means for advancing said books in succession, of a rotary presser wheel positioned to act with an ironing effect upon the successive cover flaps in a 130

plane between the fold line and the outer end of each flap, thereby imparting a transverse bend to the body of the flap.

3. In a match-book machine having a carrier for match books whereof the covers each include a fastened fold at one end and an outwardly extending flap at the opposite end, and having also means for folding the said flap and tucking its free end beneath the fastened fold of the cover, a presser device arranged in advance of the said means and positioned to act upon the successive cover flaps and impart a transverse bend thereto.

4. In a match-book machine having a carrier for match books, whereof the covers each include a fastened fold at one end and an outwardly-extending flap at the opposite end, and having also means for folding the said flap and tucking its free end beneath the fastened fold of the cover, a rotary presser wheel arranged in advance of the said means and positioned to act with an ironing effect upon the successive cover flaps and impart a transverse bend thereto.

5. In a match-book machine having a carrier for match books, whereof the covers each include a fastened fold at one end and an outwardly extending flap at the opposite end, and having also means for folding the said flap and tucking its free end beneath the fastened fold of the cover, spaced flap-supporting elements arranged in advance of the said means, and a presser device positioned to act upon the portions of the successive cover flaps bridging the space between the said elements.

6. In a match-book machine having a carrier for match books, whereof the covers

each include a fastened fold at one end and an outwardly-extending flap at the opposite end, and having also means for folding the said flap and tucking its free end beneath the fastened fold, spaced flap-supporting elements arranged in advance of the said means, and a rotary presser wheel positioned to act with an ironing effect upon the portions of the successive cover flaps bridging the space between the said elements.

7. In a match-book machine having a carrier for match books, whereof the covers each include a fastened fold at one end and an outwardly-extending flap at the opposite end, and having also means for folding the said flap and tucking its free end beneath the fastened fold, a pair of spaced wheel elements upon which the cover flaps are supported in advance of the said means, and a presser device arranged to act upon the portions of the flaps bridging the space between the said elements.

8. In a match-book machine having a carrier for match books, whereof the covers each include a fastened fold at one end and an outwardly-extending flap at the opposite end, and having also means for folding the said flap and tucking its free end beneath the fastened fold, a pair of spaced wheel elements upon which the cover flaps are supported in advance of the said means, and a freely rotatable presser wheel arranged to act with an ironing effect upon the portions of the flaps bridging the spaces between said elements.

Signed at Barberton in the county of Summit and State of Ohio this 25th day of September A. D. 1917.

MICHAEL PARIDON.
